COIN CHANGING VENDING MACHINE

Tord Olof Rickard Dahlberg, Nockeby, Sweden,
assignor to Kooperativa Förbundet Förening
U. P. A., Stockholm, Sweden

Application January 10, 1940, Serial No. 313,198
In Sweden January 14, 1939

3 Claims. (Cl. 194—80)

In coin changing vending machines for goods or the like provided with several coin insertion slots for various coin denominations, for example of the type described in British Patent No. 440,763, it sometimes happens that the coins in one of the coin receptacles become exhausted.

The object of the present invention is to produce a machine of this type in which a coin slot for such coins of a higher denomination, the insertion of which would require the delivery of change from a pile of coins of a certain lower denomination, is automatically blocked when the number of coins in the coin receptacle for said lower denomination falls below a predetermined limit, and the blocked coin slot of the higher denomination is automatically unblocked as soon as, upon insertion of another coin into the coin slot of the lower denomination, the number of coins in the coin receptacle of said lower denomination rises again above said predetermined limit.

One embodiment of the invention is illustrated in the accompanying drawings, in which

Fig. 1 is a front elevation, partly in section, of the device,

Fig. 2 is an end elevation, seen from the left hand side of Fig. 1 and partly in section, and

Figure 3 shows a section on the line III—III in Figure 1.

Reference numeral 1 denotes the casing of a vending machine for goods or tickets, said casing having five coin insertion slots intended for 5-, 10-, 25- and 50-öre pieces and for 1-krona pieces. The drawings show only the coin chute 2, the coin receptacle 3 and the delivery mechanism connected to the slot for the 5-öre pieces. The delivery mechanism consists of an ejecting member 5 adapted to be reciprocated through an aperture 34 in the wall of the coin receptacle 3 by means of a link 33 actuated by a cam disc 4 and of an arm 7 adapted to be rocked upwards and downwards by a cam disc 6. The cam discs 4 and 6 are fast on the main shaft 32 of the machine which is rotated by a motor (not shown). A plunger 8, forming the bottom of the coin receptacle 3 and provided with a groove 12, is retained by the free end of the arm 7 in the position shown on the drawings until the counting process has been finished and the delivery shaft 9 of the machine and the cam discs 10 thereon have assumed the positions corresponding to the entered amount as described in the British Patent 440,763. Then the arm 7 performs a rocking movement, and the pin 11 on the underside of the plunger 8 is allowed to move

down and, according to the angular position of the shaft 9, to bear against the periphery of the disc 10 or enter some one of the recesses made in the same. In the former case the ejecting member 5, upon being reciprocated, passes through the groove 12 in the plunger 8 and does not strike or take along any coin, while in the latter case the front end of the ejecting member strikes and pushes out one coin through a slot 13 in the front wall of the receptacle 3, as described in the above mentioned British patent.

If, for example, the vending machine above described is adjusted for a price of 15 Swedish öre, the payments will perhaps most often consist of two 10-öre pieces, and, consequently, the machine will have to pay out a 5-öre piece on every such occasion. The consequence will very likely be that the receptacle for 5-öre pieces is emptied. In such cases machines used hitherto have been closed and put out of function until the emptied receptacle has been filled again. However, thanks to the present invention the machine will continue functioning, but the insertion of such coin denominations, in the above example 10-öre pieces, as may require a delivery of 5-öre pieces, is prevented. As soon as one or more 5-öre pieces have been inserted in the machine it will be possible again to insert 10-öre pieces. According to the invention the machine itself will thus ensure that a lacking coin denomination will be supplied to the emptied receptacle again. For obtaining this purpose the following elements have been added in the embodiment shown on the drawings:

On the ejecting member 5 is rigidly mounted a bracket 14, in which a pin 15, adapted to pass with its free end through apertures 19 in the receptacle wall, is displaceably but not rotatably supported. The pin 15 has fixed thereto a laterally projecting bracket 35 carrying parallel to the pin 15 a rod 16, the free end of which has an oblique surface 17 (Figure 3), and between the bracket 14 and the bracket 35, there is interposed a helical spring 18. If the receptacle 3 contains a sufficient number of coins, the pin 15, when carried along by the displacement of the member 5, will strike with its free end against the edges of the coins and remain practically in the same position. However, since the spring 18 can be compressed, the member 5 is allowed to perform its movement. If, however, there are no more coins in the receptacle 3 than shown on the drawings, the pin 15 will enter into the receptacle 3 through an opening 19 in the rear wall thereof, when the member 5 is displaced.

Of course, the rod 16 will then also be carried along, its oblique surface 17 now cooperating with a pin 20. Said pin, which is secured to a two-armed lever 22 rockable around a shaft 21, is now forced in the direction indicated by an arrow in Figure 3, the lever 22 being thereby rocked in the direction also indicated by an arrow in Figure 1. A spring actuated locking roller 23 cooperating with the lever 22 is thereby brought out of its locking engagement with the lever 22 and the latter is forced into the position indicated by dot-dashed lines in Figure 1, in which position the locking roller has entered into locking engagement with a recess 24 provided in lever 22. The portion 25 of the lever 22 has simultaneously assumed a position in which it blocks the coin insertion slot for the 10-öre pieces. By a suitable marking 26, visible through an opening 31 in the casing 1, there may also be indicated that the said insertion slot is blocked for the present.

The lever 22 remains in its position indicated by dot-dashed lines in Figure 1 until one or more 5-öre pieces have been inserted into the slot for said coin denomination. As soon as a coin has been inserted into said coin slot, the lever 22 is automatically returned to its original position. This is effected by the following elements:

The machine described above is provided, in known manner, with reciprocable push-rod or control members 36, by means of which coins standing on edge in the coin chutes are moved from said chutes to the coin receptacles. Therefore, if a 5-öre piece has been inserted into the coin chute for said denomination, as shown in Figure 1, the push-rod member 26, when being displaced in the direction indicated by an arrow in Figure 1, will strike against said coin, whereby the latter will serve as coupling member and, against the action of a spring 27, carry along a movable portion 29 of the coin chute with a pin 28 in the above-mentioned direction. The pin 28 now contacts with a projection 30 formed from the lever 22 and, consequently, forces the lever 22 into its initial position in which it is retained by the spring biased roller 23. The coin slot for the 10-öre pieces thus becomes unblocked, and any coin denomination may again be inserted into the machine.

Of course several embodiments of the device are possible within the scope of the invention, and the device may advantageously be applied

to various vending machines for articles and tickets without the inventive idea being therefore abandoned.

Having now described my invention, what I claim as new and desire to secure by Letters Patent is:

1. In a coin receiving and change giving mechanism comprising, for each coin denomination, a coin receptacle to accommodate a pile of coins, 10 a coin chute leading to said receptacle and being provided with a coin receiving slot, and coin ejecting means to deliver coins of said denomination from said receptacle, a shiftable element, a resilient drive for said element operable to urge 15 displacement thereof in one direction, said element having a portion disposed normally in front of an aperture provided in the wall of a receptacle for coins of a lower denomination at a predetermined level to substantially prevent displacement of said element upon operation of said 20 resilient drive when the pile of coins in said receptacle projects above said predetermined level and to penetrate into said coin receptacle, thereby permitting displacement of said shiftable element by said resilient drive when the latter is 25 operated while the uppermost coin of said pile is below said level, a blocking member operatively connected with said shiftable element and adapted 30 to block the coin receiving slot of a different and higher coin denomination when said element is displaced, and means to restore said blocking member to its inoperative position when a coin has been inserted into the coin receiving slot of said first mentioned lower coin denomination.
2. A mechanism, as claimed in claim 1, in which said resilient drive comprises a resilient coupling between said shiftable element and the coin ejecting means of said lower denomination.
3. A mechanism, as claimed in claim 1, in 40 which the coin chute of said lower denomination includes a movable portion and a reciprocable member so arranged that a coin inserted into the coin slot of said lower denomination forms a connector between said reciprocable member and said movable portion to permit displacement of the movable portion by the reciprocable member when a coin has been inserted in said coin slot, said means for restoring said blocking member to its inoperative position being operatively 45 connected with said movable portion of the coin chute.
- 50 TORD OLOF RICKARD DAHLBERG.
